RICHARD M. DILWORTH, OF LAKEWOOD, OHIO, ASSIGNOR TO THE ELECTRO-MOTIVE COMPANY, OF CLEVELAND, OHIO, A CORPORATION OF OHIO

ELECTROPNEUMATIC THROTTLE CONTROL

Application filed January 19, 1931. Serial No. 509,613.

This invention relates to control means for the throttle of an internal combustion engine, the means being of the so-called electro-pneumatic type whereby remote control of the throttle may be had as is desirable in certain internal combustion installations such as in locomotive or marine practice.

The electro-pneumatic throttle control is not new per se, and as will be appreciated by one familiar with the art comprises a number of pistons usually single-acting and spring-balanced to "rest" position and movable from the latter under air pressure, these pistons being associated with the throttle of the engine to be controlled by a differential arrangement whereby the throttle may be opened step by step, by admission of air to the pistons in succession. Such admission is controlled by a number of valves one for each piston, and for remote control the valves are in turn controlled each by electric means. Usually a controller is provided for the purpose whereby the valves are related for opening in a predetermined sequence to progressively open the throttle by movement of the controller in one direction.

Thus the entire control respectively includes three systems arranged: the first, a mechanical one including the differential interassociation of the pistons with the throttle; second, a pneumatic system for actual operation of the pistons; and third, an electric system for controlling the piston valves.

The air supply is had from a compressor driven by the engine to be controlled. Thus if the "rest" position of the pistons correspond with closed or "idling" position of the throttle, air pressure is necessary to open the throttle; and if the compressor at "idling" speed has not sufficient delivery over leakage in the system it will be apparent that, as after a long period of "idling", the pneumatic control must be disconnected and the throttle opened by hand, before the compressor can supply enough air for normal pneumatic control. Such has heretofore been the practice in the art and the elimination of the necessity for such practice is the principal object of this invention.

Briefly, I accomplish this by so asso-

ciating the pistons with the throttle that the throttle is partially open when the pistons are in "rest" position, one of the pistons being arranged to close the throttle to "idling" position only under pressure from the pneumatic system. By this arrangement when the operator sets his controller or other operator-operated means to "idle" position the engine throttle will be moved correspondingly and will so remain while there is a normal or predetermined pressure maintained in the pneumatic system. But should this pressure at any time and for any reason become insufficient, the throttle will be automatically opened to increase the output of the compressor; and when the desired pressure has been rebuilt, the throttle will automatically reclose to "idling" position. Thus, at all times the pneumatic control is maintained operative subject to the will of the operator.

The exact nature of this invention together with further objects and advantages thereof will be apparent from the following description taken in connection with the accompanying drawing, in which Figs. 1 and 2 are diagrammatic and conventionalized showings of the electric and pneumatic systems respectively; Fig. 3 is a detail showing the association of the pneumatic system with the throttle of the engine to be controlled, by the mechanical or differential arrangement interposed therebetween; Fig. 4 is a detail showing the inter-association of the electric and pneumatic systems; and Fig. 5 is a detail of the electrically controlled valve means employed. In Figs. 2-4 inclusive parts appear in section to show details of construction.

With reference now to the drawing, 1 represents the throttle valve of the engine to be controlled. The valve is of butterfly type as indicated, mounted for pivotal movement in the inlet pipe 2 of the engine. 3 is a lever outside the pipe rigidly associated with the valve and 4 is a link pivoted with the lever 3 for operating the latter and thus the valve 1.

For operating the valve 1 by pneumatic power a number of pistons are provided. Thus in Fig. 3, four pistons 5, 5a, 5b, 5c, are provided each movable in its cylinder bore

as shown in the cylinder block 6. Each piston is single-acting and is backed by a spring 7. The block 6 has, for each piston, opposite the spring 7 thereof, an inlet passage 8. Thus each piston is urged by its spring 7 to "rest" position, which is that shown in Fig. 3, and is movable therefrom against its spring by fluid pressure at its inlet 8.

Each piston has a stem or rod 9 extending through and beyond the block 6, and there has a pivotal connection with a linkage. The piston 5 has connection with one end of the lever 10. The opposite end of this lever has connection with a link 11 which in turn has at its opposite end connection with an end of the lever 12. The piston 5b has connection with the lever 10 intermediate the ends of the latter by a link 13. The piston 5a has connection with one end of a lever 14 the opposite end of which has connection with the piston 5c through a link 15. The lever 14 has connection with the lever 12 intermediate the ends of the latter by means of a link 16.

The lever 12 has connection with the link 4 at its end as indicated, so that the throttle 1 may be controlled by movement of the lever 12.

The linkage described will be recognized as providing a differential relation between the four pistons and the throttle valve 1 whereby the position of the throttle is a function of the positions of the several pistons. The lever 10 is a floating lever controlled by the pistons 5 and 5b; the lever 14 is a floating lever controlled by the pistons 5a and 5c; and the lever 12 is a secondary floating lever controlled by the positions of the levers 10 and 14.

It will be observed that by this linkage pneumatic operations of all of the pistons does not produce the same effect upon the throttle valve. Movement of any of the three pistons 5a, 5b or 5c from "rest" position will effect opening of the throttle valve; and coincident movement of more than one of these three pistons will more widely open the throttle valve. But movement of the fourth piston 5 will close the throttle valve. The proportion and arrangement of the parts is such that when the pistons are all at "rest" as shown in Fig. 3, the throttle valve will be open slightly wider than for "idling" of the engine, and such that only when the piston 5 is moved from closed position, can the throttle valve move to "idling" position.

With reference now to Fig. 2, 17 represents the engine to be controlled; 18, a compressor driven by the engine; 19, a receiver into which the compressor delivers; and 20, the four cylinders in the block 6 for the pistons 5 shown in Fig. 3. Each cylinder 20 has communication with the receiver 19 through a manifold passage 21 and its inlet passage 8 subject to a valve 22.

With reference now to Figs. 4 and 5, each

valve is yieldably maintained seated as by a spring 23 to close admission of air from the passage 21 into the passage 8 of its cylinder 20. Each valve has an operating stem 24 with an annular opening 25 thereabout whereby passageway is had to the cylinder when the valve is open. On the opposite end of its stem 24 each valve 22 has a second valve 26 movable upwardly to close the lower mouth, Fig. 5, of the passage 25 when the valve 22 is unseated, and to unseat as indicated in Fig. 5 when the valve 22 is seated. The valve 27 is provided with a passage 28 one for each cylinder, whereby relief to atmosphere is had for that cylinder when the valve 22 is seated. In other words, each valve stem 24 has two positions, one in which its piston is subject to pressure from the compressor 18; and in the other of which, its "rest" position, its cylinder is relieved to the atmosphere so that its piston is subject only to its spring 7.

Each valve is controlled by electrical means such as a solenoid 29 having a coil 30 and an armature controlled by the coil and rigidly associated, as integral, with the valve 26. Thus there are four solenoids, one for controlling each piston 5. As shown in Fig. 1, these four solenoids are arranged in a controller circuit so that their coils 30 are energized dependent upon the position of a drum 31. The controller 31 has the usual contactors 32 engageable with fingers 33 dependent upon the position of the drum. The arrangement of the contactors 32 upon the controller 31 is such that controller movement will energize the solenoids 29 in a predetermined sequence as the drum is moved in one direction; and this sequence is such that the floating lever 12 will move to open or close the throttle step by step dependent upon the direction of drum movement.

The drum is operator-operated and may, of course, be located at a remote position from the solenoids 29.

Operation will be apparent. When the drum is in "idling" position the valve 22 of the piston 5 will be open but the valves 22 of the other three pistons 5a, 5b and 5c will all be closed. The throttle 1, therefore, will be moved to "idling" position. As the operator moves the drum 31 from "idling" position, first the valve 22 of the piston 5 will be moved to release the piston 5 to the action of its spring 7 and the throttle 1 will move toward open position. Further drum movement will effect opening and closing of valves 22 in predetermined order to correspondingly move the pistons 5a, 5b and 5c.

The differential linkage may preferably be of such order that by various combinations of opening of the valves of the pistons 5a, 5b and 5c, more steps of throttle opening may be had than there are pistons; but such arrangement is well known and indeed immaterial here.

When the drum is set to "idling" position and the valve 22 of the piston 5 consequently open, the throttle 1 will remain in "idling" position only so long as there is sufficient pressure in the manifold 21 to maintain the piston 5 against its spring 7. Should the air pressure fall below such amount as by leakage anywhere in the system or by exhausting the capacity of the receiver 19, the piston 5 will move to "rest" position automatically under the action of its spring 7, and the valve 1 will consequently be moved to speed up the engine. The valve 22 of the piston 5 will, however, remain open so that when the compressor 18 has built up the required pressure in the system the piston 5 will be returned by this pressure against its spring 7, reclose the throttle to "idling" position and the engine will again be running at the "idling" speed indicated by the drum position.

What I claim is:

1. In an electro-pneumatic throttle control of the class described, wherein an engine throttle is to be controlled by a plurality of pistons arranged to be separately movable in a fixed sequence from "rest" position by air from a compressor driven by the engine, differential means associating said pistons with said throttle and providing for partial opening of said throttle when all of said pistons are in "rest" position, and providing for movement of said throttle to "idle" position by movement of one of said pistons under air pressure.

2. In combination with an engine having a throttle and a compressor driven by said engine, control means for said throttle and comprising a plurality of pistons, differential mechanism associating said pistons with said throttle whereby the position of the throttle is a function of the positions of said pistons, operator-controlled means for controlling admission of air from said compressor selectively to said pistons, one of said pistons being arranged for throttle-closing movement under the pressure of said air admitted thereto, and another of said pistons being arranged for throttle-opening movement under the pressure of air admitted thereto.

3. In combination with an engine having a throttle and a compressor driven by said engine, control means for said throttle and comprising a plurality of pistons, differential mechanism associating said pistons with said throttle whereby the position of the throttle is a function of the positions of all of said pistons, operator-controlled means for controlling admission of air from said compressor selectively to said pistons, one of said pistons being arranged for throttle-closing movement under the pressure of said air admitted thereto and having associated means providing for throttle-opening move-

ment in the absence of said pressure, and the other pistons being arranged for throttle-opening movement under the pressure of said air admitted thereto.

4. In combination with an engine having a throttle and a compressor driven by said engine, control means for said throttle comprising a plurality of single-acting pistons, differential mechanism associating said pistons with said throttle whereby the position of the throttle is a function of the positions of all said pistons, operator-controlled valve means for controlling admission of air from said compressor selectively to said pistons, one of said pistons being arranged for throttle-closing movement under the pressure of said air admitted thereto, and the other pistons being arranged for throttle-opening movement under the pressure of said air admitted thereto, each of said pistons having associated means providing for its movement in the opposite direction from that effected by air pressure.

5. In combination with an engine having a throttle and a compressor driven by said engine, control means for said throttle and comprising a plurality of pistons, differential mechanism associating said pistons with said throttle whereby the position of the throttle is a function of the positions of all of said pistons, operator-controlled means for controlling admission of air from said compressor selectively to said pistons, one of said pistons being arranged for throttle-closing movement under the pressure of said air admitted thereto and having associated means providing for throttle-opening movement in the absence of said pressure, and the other pistons being arranged for throttle-opening movement under the pressure of said air admitted thereto, and operator-operated means associated with said operator-controlled means for providing for a predetermined sequence of admission to said pistons whereby the progression of admission will be to effect opening the throttle as the operator-controlled means is moved in one direction, and vice versa.

In testimony whereof I hereby affix my signature.
